TAPE REEL

William S. Sheppley, Jr., Rhinebeck, N.Y., assignor to
International Business Machines Corporation, New
York, N.Y., a corporation of New York

Filed May 19, 1964, Ser. No. 80,049

Term of patent 14 years

(Cl. D61—1)

FIG. 1

FIG. 2

FIG. 3

FIG. 1 is a front elevational view of a tape reel showing my new design;

FIG. 2 is a rear elevational view thereof; and

FIG. 3 is a side elevational view thereof.

The characteristic features of my design reside in the three holes located near the center of the reel and the raised beading forming the appearance of spokes about the hole and the periphery of the reel.

I claim:

The ornamental design for a tape reel, substantially as shown and described.
